[57] CLAIM

The ornamental design for a stool for invalids or the like, as shown.

DESCRIPTION

FIG. 1 is a perspective view taken from the top, rear and right side of a stool for invalids or the like showing my new design, with the seat in a raised position; FIG. 2 is an enlarged rear perspective view of the removable rack;

FIG. 3 is a top plan view thereof showing the seat in its down position;

FIG. 4 is a bottom plan view of FIG. 3;

FIG. 5 is a front elevational view of FIG. 3;

FIG. 6 is a rear elevational view of FIG. 3; and

FIG. 7 is a left side elevational view of FIG. 3.
